(57) **CLAIM**

The ornamental design for a filter pump, as shown and described.

DESCRIPTION

FIG. 1 is a front perspective view of the filter pump showing my new design.

FIG. 2 is a front view of the filter pump

FIG. 3 is a rear view of the filter pump

FIG. 4 is a left side view of the filter pump

FIG. 5 is a right side view of the filter pump

FIG. 6 is a top view of the filter pump; and,

FIG. 7 is a bottom view of the filter pump.

The broken lines showing features of the filter pump form no part of the claimed design.
